UNITED STATES PATENT OFFICE.

JOHN J. HOGAN, OF BROOKLYN, NEW YORK, ASSIGNOR TO THE HOGAN
ENGINEERING COMPANY, OF NEW YORK.

WATER-LEG FIRE-BOX.

SPECIFICATION forming part of Letters Patent No. 425,943, dated April 15, 1890.

Application filed December 7, 1889. Serial No. 332,994. (No model.)

To all whom it may concern:

Be it known that I, JOHN J. HOGAN, a citizen of the United States, residing at Brooklyn, Kings county, New York, have invented 5 certain new and useful Improvements in Water-Leg Fire-Boxes, fully described and represented in the following specification and the accompanying drawings, forming a part of the same.

10 My present improvements relate especially to the fire-box of a water-heating boiler for use in connection with hot-water radiators, and the construction shown in the drawings is adapted to be used with additional water- 15 sections superposed thereon, as shown in my patent applications, Serial Nos. 292,642 and 316,150.

The invention will be understood by reference to the annexed drawings, in which— 20 Figure 1 is an elevation of the construction, viewed from the fire-door side. Fig. 2 is a vertical section on line $z z$ in Fig. 3. Fig. 3 is a plan of the under side of section C of the boiler. Fig. 4 is a vertical section on 25 line $z' z'$ in Fig. 3 and $x' x'$ in Fig. 5 with a breeching applied to the top. Fig. 5 is a sectional plan on line $x x$ in Fig. 4. Fig. 6 is a sectional plan on line $y y$ in Fig. 4; and Figs. 7 and 8 are a plan and vertical section through 30 the center of the water column and a portion of the pocket g beneath the same, upon a large scale, to show the thimble-connections.

The fire-box consists in three cast-iron sections A, B, and C and ash-pit D, provided 35 with grate E. The section A encircles the fire-pot and is lined with fire-brick. The section B surrounds the combustion-chamber above the fire-pot, and the section C forms a dome or cover to the fire-box. The sections 40 A and B consist in annular water-jackets, the lower section around the fire-pot being divided by an internal vertical partition into two water-channels, one contiguous to the fire and the other to the exterior of the section. In section A, s is the partition; e , the 45 water-channel next the fire-box; d , the exterior channel.

The water-channels are closed at the top and bottom and the interior channel is provided with several pockets g , projected toward the fire in the fire-pot and provided

upon their upper sides with thimble openings h to connect with the section B. An inlet-nozzle i for the return-fluid from the radiator system is provided at the rear of the section A and admits the fluid to the channel d , as indicated by the arrows a' in Fig. 5.

An aperture k is formed in the partition s at the opposite side of the section to admit the water from the channel d to the channel e and thimble-openings h , as shown by the arrow o' in Fig. 5. A deflector k' is provided at the middle of the opening k to deflect the water in two currents in opposite directions into the channel e toward the thimble-openings h .

The section B contains but one water-channel d' and is provided internally with three water columns g' , arranged vertically over the pockets g and connected thereto by thimbles l , inserted in the openings h . These water columns are open laterally into the channel d' , so that the water passes freely from the channel into all the columns. The section is provided externally with several pockets m , communicating freely with the same channel, 70 and the upper sides of the pockets are formed with thimble-openings n , by which they are connected by the thimbles o with similar pockets p upon the upper section C. This section is a flat hollow plate forming the 75 crown or top of the fire-box and is provided with thimble-openings h^2 for connecting it with the pockets g' by thimbles l' . The upper surface of the plate is dome-shaped or highest in the middle, the center being provided 80 with the outlet-nozzle Q , from which the heating-fluid would be conducted to the heating-radiators or into the upper sections of the boiler, if such were used. The pockets g' upon the inner side of the section B project 85 prominently into the combustion-chamber and operate as vertical water columns to receive the strongest effect of the fire and to produce a strong upward circulation from the lower section A into the upper section C. 90 The circulation in the water columns g' and the thimbles o is shown by arrows o' in Fig. 2. Such an upward movement of the fluid would tend to the generation of steam where the water was displaced and to the overheating 100 of the metal in the water columns and in the lower section. Such tendency is, however,

wholly corrected by the provision of the external thimbles *o*, which connect the outer part of the upper section with the outer part of the section *B*, and thus provide an ample 5 passage for the downward movement of the colder fluid to supply the place of that which is heated in the water columns. My previous applications referred to herein also show provision for such downward circulation in the 10 exterior water-channels that are colder than the water-space of the boiler, and my present application differs from such constructions partly in the use of an annular partition in one or more of the boiler-sections to divide 15 the same into internal and external water-channels, partly in the combination of the water columns *g'* with the section around the fire-box, and partly in the entire construction shown herein, in which the lower section 20 alone is divided into inner and outer water-channels and receives the return-fluid in the outer channel. Such return-fluid is prevented by the partition *s* from contact with the heated metal close to the fire, and is materially 25 warmed by its contact with the partition *s*, through which heat is conducted from the hotter contents of the channel *e*, before it enters said channel.

In Figs. 3 and 4 smoke-passages *v* are 30 shown, perforating the top section, the walls of which passages intersect the water-space within the section, and in Fig. 4 a breeching *H* is shown applied over the top of such section, with a smoke-pipe *I* to carry off the products of combustion.

In case it were desirable to increase the capacity of the boiler, other sections similar to the sections *C* would be superposed thereon and connected at the pockets *p* and central 40 nozzle *Q*, the water columns extending only upward to the lower side of the section *C*, and such construction for the superposed sections is shown in my before-mentioned applications, but forms no part of my present invention. 45

It will be understood that the water columns *g'* present a comparatively small body of water (somewhat isolated from the adjacent water-ring) to the intensest heat of the 50 fire, and thus secure the absorption of such heat in the most effective manner in a portion of the water which is most favorably located for a direct upward movement.

As shown in Fig. 4, the water columns *g'* 55 form a direct vertical passage from the inner channel *e* in the fire-pot ring to the interior of the crown-plate *C*, so that the upward

movement of the water in the water columns tends most forcibly to draw a continuous current of fluid from the vicinity of the fire-pot 60 and force it in a highly-heated condition into the upper water-section of the boiler. As the water-rings form a hollow water-leg like that in an upright wrought-iron boiler, I have termed my invention a "water-leg fire-box." 65

Having thus set forth the nature of my invention, what I claim herein is—

1. In a boiler having a number of hollow sections superposed one upon another, an annular hollow section around the fire-pot provided with an external water-inlet, an annular vertical partition opposed to such inlet and forming inner and outer water-channels within the ring, an aperture in the partition for the passage of the water to the inner channel, and one or more apertures conducting the water upward from such inner channel to the water-sections above, as and for the purpose set forth. 75

2. In a boiler, the combination, with the annular section *A*, provided with the annular partition *s*, forming outer channel *d*, having inlet *i*, and inner channel *e*, provided with thimble-openings *h*, of the annular section *B*, having a single water-channel provided internally with the water columns *g'* and with the pockets *m*, having thimble-openings *n*, and the section *C*, provided with thimble-openings, and thimbles connecting the section *C* with the pockets *m* and water columns *g*, as and for the purpose set forth. 80

3. In a boiler, the combination, with the annular section *A*, provided with the annular partition *s*, forming outer channel *d*, having inlet *i*, and inner channel *e*, provided with thimble-openings *h*, of the annular section *B*, having a single water-channel provided internally with the water columns *g'* and with the pockets *m*, having thimble-openings *n*, and the section *C*, provided with thimble-openings, and thimbles connecting the section *C* with the pockets *m* and water columns *g*, the section *B* having an opening in one side for the fire-door, and the several sections being separated by smoke-spaces *u* and provided with marginal flanges *t* to confine the smoke to such spaces, substantially as herein set forth. 95 100 105

In testimony whereof I have hereunto set my hand in the presence of two subscribing witnesses.

JOHN J. HOGAN.
